Carpets

EXAMINER'S ROOM.

No. 6,138

Sept. 10- 1872

UNITED STATES PATENT OFFICE.

GEORGE C. WRIGHT, OF NEW YORK, N. Y., ASSIGNOR TO E. S. HIGGINS & CO., OF SAME PLACE.

DESIGN FOR CARPET.

Specification forming part of Design No. 6,138, dated September 10, 1872.

Specification describing a Design for Carpets, invented by GEORGE C. WRIGHT, of New York, county of New York and State of New York.

The nature of my design is fully represented in the accompanying photographic illustration, to which reference is made.

K and L represent two panels, K being square and L a parallelogram, both of the Gothic order. Figure A is the center, formed by a band in mottled work c c, outside of which is a band composed of *fleur-de-lis* x and spade-shaped figures d d d; then a band or line, e, which, with D D, dart, and shield, (modified,) completes the figure K. E is a panel outlined with a band, I, and scrolls g g, resting on a plain ground, the border of which is composed of spear-head figures, F, in regular order; G, scroll-work, composed of trefoils and *fleur-de-lis*, forming a vine-work around F and *fleur-de-lis*, forming a vine-work around F and resting on ground k and l; H, a band formed by line or band around ground l, and composed of shields in regular order.

I prefer to make ground y drab; l, white; H, alternately green and scarlet; D D, alternately red, scarlet, blue, and green; c c, brown, white, drab; K, scarlet; E, scarlet with dark maroon outline; B, scarlet.

I do not consider the colors selected to be an essential element in my design.

I am aware that carpet-patterns composed of Gothic bands, *fleur-de-lis*, trefoils, and set figures is not new, and lay no claim to those features. The distinctive character of my design is found in the construction of bands forming panels, in combination with *fleur-de-lis*, scroll-work, and set figures.

What I claim as my invention is—

A design for carpet, in which the panels, bands, *fleur-de-lis*, and scroll-work are combined, substantially in the manner above described.

GEO. C. WRIGHT.
